UNITED STATES PATENT OFFICE.

GUSTAV NETTLE, OF LEABURG, OREGON.

SNATCH-BLOCK.

No. 831,460.

Specification of Letters Patent.

Patented Sept. 18, 1906.

Application filed January 4, 1906. Serial No. 294,606.

To all whom it may concern:

Be it known that I, GUSTAV NETTLE, a citizen of the United States, residing at Leaburg, in the county of Lane and State of Oregon, have invented certain new and useful Improvements in Snatch-Blocks; and I do hereby declare the following to be a full, clear, and exact description of the invention, such as will enable others skilled in the art to which it appertains to make and use the same.

My invention relates to what are known as "snatch-blocks" for pulleys—that is, blocks so constructed and arranged that the swinging cross-head thereof may be thrown back on its pivot to receive the bight of a rope, chain, or cable without the trouble and annoyance of reeving the end through—but more particularly to logging-blocks for use in logging-camps with engines and cables. Among the other uses for which my device is well adapted are for elevators and ferries.

Generally stated, the object is to provide an improved, novel, and simple form of such blocks.

Another object is to construct the device of my invention of a minimum number of parts, which shall be extremely inexpensive to manufacture. In many constructions where logging is done with engines the pulley of the block turns on a pin, and in spite of utmost care and careful oiling friction cannot be overcome, and the pin frequently burns out. By the peculiar formation of my device binding and friction of the working parts are reduced to a minimum, ninety per cent. of usual friction being eliminated, and there is a saving of seventy-five per cent. of lubricant, twenty-five per cent. of wear on the cable, and twenty five per cent. of power required. In many constructions also the full weight or tension of the cable on the pulley comes on the block carrying the pulley.

Another object, therefore, is to relieve the block of my device of such strain, and I effect this by providing a novel form of straps (hereinafter described) which receive the strain of the line or cable. I am also enabled by the use of my strap to raise one face or jaw of the block to fill the lubricant-chamber, if necessary, while the line or cable is tight on the pulley and without any danger of the pulley becoming disengaged from and falling out of the block.

Moreover, the object of my invention is to improve the general and specific construction of the device forming the subject-matter of my Patent No. 779,437.

In my present device the specific improvements and differences over my patented structure reside, among others, in the particulars noted, as follows:

First. I form the front (or each) jaw, shell, or frame-plate of the block with an extended cut-away portion for the reception of a strap and with a transverse securing-strip extending transversely of the cut-away portion and the jaw, all for purposes hereinafter appearing.

Second. I form the sheave or pulley with a central countersunk portion on each of its front and rear surfaces, for a purpose hereinafter appearing. Also instead of having the exits of the oil-holes in the raceway of the antifriction-balls (as in my patented device) I form the exits at the countersunk portions of the pulley, thus preventing the oil-holes being stopped up by dirt, dust, &c., as they would when their exits are in the raceway, and I provide efficient means for protecting the oil-holes from entrance of outside dirt and dust and for preventing the oil from running out onto the exterior surfaces of the block, all as hereinafter explained.

Third. I form the cone disposed in the central opening of the sheave or pulley with removable bushings or sleeves, the object of these removable sleeves or bushings being to overcome wear on the cone, the sleeves by being removable being capable of being replaced when worn by new ones at very little cost.

With these and other object in view the invention consists in and comprehends the novel construction, combination, and arrangement of parts of a device characterized by my invention, as hereinafter fully described in the specification, summed up in the claims, and illustrated in the drawings.

In the accompanying drawings, Figure 1 is a front elevation of my device, the swinging cross-head when thrown up for insertion of a loop or bight of rope without the necessity of having to reeve the end through being indicated in dotted lines. Fig. 2 is a side elevation of my device, the front jaw being thrown open and upward for the purpose of permitting filling of the oil or lubricant chamber in

the sheave: Fig. 3 is a perspective view, partly in section, showing the sheave or pulley removed from the device. Fig. 4 is a perspective view of the cone removed from the device. Fig. 5 is a detail perspective view of one of the detachable members forming the cone. Fig. 6 is a detail perspective view of the other member thereof. Fig. 7 is a detail perspective view of one of the removable bushings or sleeves of the cone. Fig. 8 is a detail view of the axle-pin of my device. Fig. 9 is a vertical transverse section through my sheave with the cone therein.

Referring in detail to the drawings, the block, as shown, comprises two jaws, shells, or frame-plates A A', of any suitable material, preferably of some metal, such as iron or steel, and of the shape shown, by preference with a substantially circular or bulged lower portion and a reduced neck-like upper portion, terminating in end knobs a' a'. From the top of the front jaw A to a point desirably below the center of the bulged lower portion I cut away the jaw, as shown at a². In this instance the front jaw only is so cut away; but the other jaw A' may also be similarly cut away, if desired.

Extending transversely of the face or front jaw A and desirably disposed toward the top of the bulged portion thereof and extending across the cut-away portion is a retaining-strip a³, provided midway of its ends with an opening a⁴.

Adapted to be disposed in and exactly to fit the cut-away portion a² is a strap a⁵, provided with a perforation a⁷, registering with the opening a⁴ and with two end knobs a⁷, the strap between the knobs being cut away, as at a⁸. A headed pin a⁹ is screwed transversely through the alining openings a⁴ a⁷, thus temporarily holding the jaw A and the strap a⁵ against independent movement. A bolt a⁶ passes transversely through the strap a⁵ and the plate A', and a nut a¹⁰, screwed on each end of the bolt, clamps together the jaw A' and the strap a⁵.

In the cut-away portion a² is adapted to fit one end of a swinging cross-head a¹², the other end fitting in a similar cut-away portion a¹³ of the rear or back jaw A', the swinging cross-head carrying the usual strong swiveled hook, eye, or ring B. A removable dowel-pin a¹⁴ passes through the various knobs, as shown, affording pivotal action of the jaws on such dowel-pins.

Supported between the two jaws A A' is a pulley or sheave C, which may be of any suitable material, such as steel or iron, case-hardened and tempered, and has the usual central opening C' and is provided on each face with similar countersunk portions c and (preferably on one face only) with a series of screw-plugs c', disposed in openings or passages c^x, leading to an annular lubricant-chamber c², located internally and concentrically of the pulley and whereby the lubricant-chamber may be supplied with suitable lubricant, a number of these screw-plugs being provided, preferably so that the lubricant-chamber may be filled at any time, no matter what may be the position of the pulley, by simply unscrewing one of the headed pins a⁹ and swinging up and back the jaw A on its pivot dowel-pin, as shown in Fig. 2.

Inclined passages c³ lead from the internal lubricant-chamber and have their exits c⁶ in the countersunk portions c, grooves c⁷ leading thence to the edge of and emptying into the opening C'. The wall of opening C' is hollowed or dished out, as shown at c⁸, to form part of a raceway for the antifriction balls or rollers hereinafter described.

Adapted to occupy the opening C' of the sheave is a cone formed in two sections or members, one member, constituting the top section, comprising a circular plate D, provided with a central opening d and an internal-threaded neck portion d², surrounding the opening d. Surrounding the neck d² is a removable bushing or sleeve d³, at the top downward and outward beveled, as at d⁴. The other member of the cone, constituting the base-section, comprises a similar circular plate D', provided centrally with a circular offset portion d⁵, terminating in a reduced externally-threaded neck d⁶ to engage the internally-threaded neck d² of the other member, a square opening d⁷ being drilled through the plate, the circular offset portion, and the neck, as shown. Surrounding the circular offset portion d⁵ is a removable bushing or sleeve d⁸ at the top downward and outward beveled, as shown at d⁹. When the two sections of the cone are screwed together, the bevels d⁴ and d⁹, together with the dished-out portion c⁸ of the sheave, constitute a raceway for antifriction balls or rollers d¹⁰. To assemble the cone with the sheave, the base member of the cone is inserted in the central opening C' of the sheave and the balls inserted around the raceway. The other member of the cone is then screwed down upon the base member, preventing falling out of the balls.

The bushings or sleeves d³ d⁸ are made removable, so that they can be replaced as worn by new bushings at very little cost, and these bushings are valuable as overcoming wear which would otherwise come on the cone. Therefore the bushings are an important feature of my present invention.

It will be noted that the plates or flanges D D' of the cone rest in the countersunk portions c, covering the oil-exits c⁶ and the oil-grooves c⁷, preventing entrance of outside dirt and dust thereto. This also is another valuable feature of my invention.

As shown in Fig. 8, the axle-pin a⁶ is square in cross-section. This pin, supporting the cone by passing through the central

square opening thereof, holds the same rigid against movement, the sheave or pulley turning on the cone easily and smoothly through the medium of the interposed anti-friction balls or rollers.

The circular flanges D D' of the cone when the two sections of the cone are screwed together extend slightly beyond the level or plane of each face-surface of the pulley or sheave, so that when my device is in operative position the strap or straps a^5 (where two are employed) rest on the flanges D D', thus giving the pulley free movement or play at all times and obviating any possible binding. In the devices of many patents there are no means shown or provided to stay the shells apart when in position, so that when a heavy weight is placed on the rope passing over the pulley in these previous constructions it causes the shells to bear in upon the pulley, binding it so tightly as to prevent turning or rotation thereof with any degree of ease and facility. My peculiar construction remedies this difficulty.

The wear strap or straps a^5 form a valuable feature of my invention, as they receive the strain of the line or cable, which would otherwise come entirely on the jaws of the block.

Various minor modifications in the nature of detail will readily suggest themselves to those skilled in the art; but all such slight changes not involving a departure from the spirit of my invention come clearly within the scope and purview thereof.

Having thus fully described my invention, what I claim as new, and desire to secure by Letters Patent, is—

1. In a snatch-block, two jaws, provided each with a long opening or slot cut transversely therethrough and extending from the top toward the bottom thereof, straps or plates fitting in said openings, and means for holding the jaws spaced apart.

2. In a snatch-block, two jaws, provided each with a long opening or slot therethrough, extending from the top toward the bottom thereof, straps or plates fitting in said openings, and means for holding the jaws spaced apart, such means also holding together the jaws and the straps.

3. In a snatch-block, two jaws, provided each with a long opening or slot therethrough, extending from the top toward the bottom thereof, straps or plates fitting in said openings, and means for holding the jaws spaced apart, such means also holding together the jaws and the straps and permitting pivotal movement of the jaws thereon.

4. In a snatch-block, two jaws, provided each with a long opening or slot therethrough, extending from the top toward the bottom thereof, straps or plates fitting in said openings, and means for holding the jaws spaced apart, such means also holding together the

jaws and the straps and permitting pivotal movement of the straps thereon.

5. In a snatch-block, two jaws, provided each with a long opening or slot therethrough, extending from the top toward the bottom thereof, straps or plates fitting in said openings, and means for holding the jaws spaced apart, such means also holding together the jaws and the straps and permitting pivotal movement thereon of said jaws and straps.

6. In a snatch-block, two jaws provided each with a long opening or slot therethrough, extending from the top toward the bottom thereof, straps or plates fitting in said openings, means located at the top of the jaws and the straps for spacing the jaws apart, such means also holding together the jaws and the straps, and additional means, located below and independent of the first-mentioned means, for temporarily securing the jaws and the straps against independent movement.

7. In a snatch-block, two jaws, provided each with a long opening or slot therethrough, extending from the top toward the bottom thereof, straps or plates fitting in said openings, a swinging cross-head for spacing the jaws apart, and means engaging the cross-head, the jaws and the straps for holding together the jaws and the straps relative to the cross-head.

8. In a snatch-block, two jaws, provided each with a long opening or slot therethrough, extending from the top toward the bottom thereof, straps or plates fitting in said openings, a swinging cross-head for spacing the jaws apart, and means engaging the cross-head, the jaws and the straps for holding together the jaws and the straps relative to the cross-head, and constructed to permit pivotal movement of the jaws and the straps.

9. In a snatch-block, two jaws, provided each with a long opening or slot therethrough, extending from the top toward the bottom thereof, straps or plates fitting in said openings, a swinging cross-head for spacing the jaws apart, and means engaging the cross-head, the jaws and the straps for holding together the jaws and the straps relative to the cross-head, and constructed to permit independent pivotal movement of the jaws and the straps thereon.

10. In a snatch-block, two jaws, provided each with a long opening or slot therethrough, extending from the top toward the bottom thereof, straps or plates fitting in said openings, a swinging cross-head for spacing the jaws apart, and a dowel-pin passing through the cross-head, the jaws and the straps.

11. In a snatch-block, two jaws, provided each with a long opening or slot therethrough, extending from the top toward the bottom thereof, straps or plates fitting in said openings, a swinging cross-head for spacing the

- 5 jaws apart, means engaging the cross-head, the jaws and the straps for holding together the jaws and the straps relative to the cross-head, and constructed to permit pivotal movement of the jaws and the straps thereon, and strips or bars disposed transversely of and secured to the jaws and constructed to permit temporary clamping of the jaws and the straps against independent movement.
- 10 12. In a snatch-block, two jaws, provided each with a long opening or slot therethrough, extending from the top toward the bottom thereof, straps or plates fitting in said openings, a swinging cross-head for spacing the jaws apart, means engaging the cross-head, the jaws and the straps for holding together the jaws and the straps relative to the cross-head, and constructed to permit pivotal movement of the jaws and the straps thereon,
- 15 20 strips or bars disposed transversely of and secured to the jaws, the straps and the transverse strips being provided with alining openings, and means passing through said openings for temporarily clamping the jaws and the straps against independent movement.
- 25 13. In a snatch-block, two jaws, provided each with a long opening or slot therethrough, extending from the top toward the bottom thereof, straps or plates fitting in said openings, and provided with openings therethrough near their lower ends, a swinging cross-head for spacing the jaws apart, means engaging the cross-head, the jaws and the straps for holding together the jaws and the straps relative to the cross-head, and means passing through the openings in the lower ends of the straps for temporarily securing them against independent movement.
- 30 14. In a snatch-block, two jaws carrying a pulley and provided each with a long opening or slot therethrough extending from the top toward the bottom thereof, said pulley being provided with a central opening and with countersunk portions, in each face, adjacent to said opening.
- 35 40 15. In a snatch-block, two jaws carrying a pulley and provided each with an extended opening or slot therethrough running from the top to a point toward the bottom thereof, said pulley being provided with a central opening, with countersunk portions, in each face, adjacent to said opening, and with an internal lubricant-chamber.
- 45 50 16. In a snatch-block, two jaws carrying a pulley and provided each with a long opening or slot therethrough extending from the top
- 5 to a point toward the bottom thereof, said pulley being provided with a central opening and with countersunk portions, in each face, adjacent to said opening, and a ball-bearing cone disposed in the central opening of the pulley.
17. In a snatch-block, two jaws carrying a pulley and provided each with a long opening or slot therethrough extending from the top to a point toward the bottom thereof, said pulley being provided with a central opening, and a ball-bearing cone disposed in the central opening of the pulley and formed in two sections, and flanges adapted to fit in the countersunk portions.
18. In a snatch-block, two jaws carrying a pulley and provided each with a long opening or slot therethrough extending from the top to a point toward the bottom thereof, said pulley being provided with a central opening and with countersunk portions, in each face, adjacent to said opening, and a ball-bearing cone disposed in the central opening of the pulley and formed in two sections, and provided with flanges adapted to fit in the countersunk portions of the pulley.
19. In a snatch-block, two jaws carrying a pulley and provided each with a long opening or slot therethrough extending from the top to a point toward the bottom thereof, said pulley being provided with a central opening and with countersunk portions, in each face, adjacent to said opening, and a ball-bearing cone disposed in the central opening of the pulley and formed in two sections, and provided with flanges adapted to fit in the countersunk portions of the pulley, each said section of the cone being provided with removable bushings or sleeves on which the balls run.
20. In a snatch-block, two jaws carrying an automatic, self-lubricating pulley and provided each with a long opening or slot therethrough extending from the top to a point toward the bottom thereof, and straps or plates fitting in said openings, said pulley being provided with a central opening and with countersunk portions, on each face, adjacent to said central opening.

In testimony whereof I affix my signature in the presence of two subscribing witnesses.

GUSTAV NETTLE.
